UNITED STATES PATENT OFFICE.

GERALD C. WATERHOUSE, OF PASADENA, CALIFORNIA.

TRAFFIC SIGNAL.

Application filed October 6, 1924. Serial No. 741,823.

To all whom it may concern:

Be it known that I, GERALD C. WATERHOUSE, a citizen of the United States, and resident of Pasadena, in the county of Los Angeles, State of California, have invented new and useful Improvements in a Traffic Signal, of which the following is a specification.

This invention relates to a traffic control signal generally of the semaphore type and adapted to be placed at points of intersections of traffic streams. In the control of traffic, it is desirable to have a semaphore which signals the traffic so that it moves alternately from intersecting directions. It has been found advantageous to employ motor actuated semaphores. The control is much more efficient, if the signal is of the preindicating type wherein the time of change from "Go" to "Stop" and vice versa is indicated.

The primary object of this invention is to provide a signal of the character described which has a single member acting as a preindicator and control signal. In addition to the broader objects of this invention, there are certain details of design leading to simplicity and economy of structure and certainty of operation.

These objects together with other objects and corresponding accomplishments are obtained by means of the embodiment of my invention illustrated in the accompanying drawing, in which:

Fig. 1 is a front elevation of a complete signal made in accordance with my invention; Fig. 2 is a side elevation of the head; and Fig. 3 is a front elevation of the head with the semaphore member in another position.

Referring more particularly to the drawing, 5 indicates a standard of any suitable design. Mounted upon the top of the standard is a head comprising a housing 6 having a slot 7 at one side thereof for the projection of the semaphore arms. Journalled upon a shaft 8 in the housing and at the edge of the slot is the semaphore member 9 comprising two oppositely disposed arms, one arm being marked on both sides with the word "Go" and the other being marked with the word "Stop." The semaphore member is arranged so that when it is in a vertical position, both arms are substantially wholly within the housing. It is intended that the semaphore members

rotate and advance preferably in a uniformly continuous manner. To this end, I have indicated a driving mechanism 10 which may be an electric motor suitably geared to the semaphore. However, the semaphore member actuating member forms no part of the present invention. Suitable bells, lights, etc., may be arranged to be operated at the same time as the semaphore members.

It is intended that while the semaphore arm having the word "Go" is exposed to view, traffic facing the semaphore arm will move, and while the arm "Stop" is exposed to view, traffic facing the semaphore arm will halt. The motor operates the arm so that it moves continuously and traffic moves while the arm "Go" moves from the upper position as indicated in Fig. 1 until it reaches its lower position, thereafter the arm marked "Stop" appears and traffic halts. It is obvious that the progressively moving arm preindicates the control signal. If the arm "Go" is just leaving the housing at the top, it is evident that it will be some time before traffic is halted. In the same manner if the arm "Stop" has just emerged from the top of the casing into view, it is obvious that the traffic will be halted for some time. The moment of change of signals is also clearly indicated.

What I claim is:

1. A traffic control signal comprising a casing having a slot at one side thereof, a signalling member rotatably mounted in said casing at said slot, said signalling member having signal indicia marked thereon whereby different indicia are projected from said casing and displayed during the rotation of said signalling member, and means to progressively rotate said member.

2. A traffic control signal comprising a casing having a slot at one side thereof, a signalling member rotatably mounted in said casing at said slot, said signalling member comprising opposite arms, said member being mounted so that one arm is concealed while the other arm is displayed, signal indicia on said arms, and means to progressively rotate said member in one direction so as to alternately display said indicia.

In witness that I claim the foregoing I have hereunto subscribed my name this 24th day of September, 1924.

GERALD C. WATERHOUSE.
